J. W. CONNATY.
SLIDING TOP FOR CABINETS.
APPLICATION FILED JUNE 1, 1908.

901,887.

Patented Oct. 20, 1908.

UNITED STATES PATENT OFFICE.

JAMES W. CONNATY, OF INDIANAPOLIS, INDIANA, ASSIGNOR TO G. P. McDougall & SON, OF INDIANAPOLIS, INDIANA, A CORPORATION OF INDIANA.

SLIDING TOP FOR CABINETS.

No. 901,887.

Specification of Letters Patent.

Patented Oct. 20, 1908.

Application filed June 1, 1908. Serial No. 436,113.

To all whom it may concern:

Be it known that I, JAMES W. CONNATY, a citizen of the United States, residing at Indianapolis, in the county of Marion and State of Indiana, have invented certain new and useful Improvements in Sliding Tops for Cabinets, of which the following is a specification.

Difficulties have been heretofore experienced, in the manufacture of kitchen and other cabinets in the formation of a sliding top member owing to the fact that, with existing constructions, the sliding portion of the top had to be somewhat less in extent than the entire top, owing to the necessity of provision of guiding members at the edges, and in practice it has been found that the horizontal joints between the sliding member and the fixed guides will readily become filled with flour, water, etc., so that the parts quickly become distorted.

The object of my present invention is to provide a structure by means of which all difficulty of this kind is avoided and the sliding member will comprise the entire top plate of the cabinet or table portion of the structure.

The accompanying drawings illustrate my invention.

Figure 1 is a perspective view of a cabinet embodying my improved structure; Fig. 2 a transverse sectional detail; Fig. 3 a perspective detail of the plate which forms the essential feature of my invention; Fig. 4 a longitudinal vertical sectional detail on a smaller scale.

In the drawings, 10 indicates the main body or table portion which, at its upper end, is provided with frame members 11. The frame members 11 which are the sides of the structure are rabbeted at their rear ends to receive a plate 12 which is substantially U-shaped in transverse section the upper lip 13 being substantially parallel with the lower lip but conveniently somewhat shorter, and a distance from the main body of the plate a trifle greater than the effective thickness of the sliding top 14, said sliding top being conveniently formed of a wooden core and an incasing metal cover 15. Lip 13 of plate 12 is provided upon its upper face, with an upwardly extending flange 16 set back from the inner

edge of the lip 13 a distance sufficient to form a pocket 17 for the reception of the lower ends of the side plates 18 of the upper structure 19, the lower ends of the plates 18 resting in the pockets 17 and being secured to flange 16 by any suitable means, such for instance as screws 19. If desired, roller supports 21 may be placed in the side bars 11 to support the forward end of the sliding top 14.

I also find it convenient to secure to the under side of sliding top 14 a cam stop 22 which, when the top 14 is drawn forwardly to the position indicated in dotted lines in Figs. 1 and 4, will ride up over the forward bar 11 and drop down in front of the same so as to form a stop to normally prevent return movement of the top 14 unless the same shall have been first raised at its front end so as to permit the cam 22 to clear bar 11. A stop bar 23 is also secured to the under side of top 14, to engage the rear bar 11 to prevent too great rearward movement of top 14, and to engage the front bar 11, to prevent too great forward movement of top 14.

The line of bend in plate 12, by which lip 13 is formed, may be extended to any desired practical extent beyond the outer edges of the side bars 11 so that top 14 may be given any desired overhang, as clearly shown in the drawings but this overhang does not in any way interfere with the proper support of the upper cabinet 19 nor does it require any undue overhanging of this cabinet beyond the lower cabinet 10.

I claim as my invention:

1. A kitchen cabinet comprising a main table structure having a forwardly sliding top, a pair of U-shaped plates having their lower arms secured to opposite sides of the table structure at the rear corners thereof beneath the top and their upper sides loosely overlapping the rear corners of the sliding top, and a cabinet superstructure secured to the upper arms of the U-shaped plates.

2. A kitchen cabinet comprising a main table structure having a forwardly sliding top, a pair of U-shaped plates having their lower arms secured to opposite sides of the table structure at the rear corners thereof beneath the top and their upper sides loosely overlapping the rear corners of the sliding

top, a vertical flange carried by the upper face of each of the upper arms of said U-shaped plates, and a cabinet superstructure mounted upon the upper arms of the U-shaped plates and secured to said vertical flanges.

In witness whereof, I have hereunto set

my hand and seal at Indianapolis, Indiana, this twenty-ninth day of May, A. D. one thousand nine hundred and eight.

JAMES W. CONNATY. [L. s.]
Witnesses:

ARTHUR M. HOOD,
THOMAS W. McMEANS.
